US0D1062677S

(12) **United States Design Patent** (10) **Patent No.:** **US D1,062,677 S**
(45) **Date of Patent:** **** Feb. 18, 2025**

(54) **MOBILE PHONE**

(71) Applicant: **GUANGDONG OPPO MOBILE TELECOMMUNICATIONS CORP., LTD.**, Guangdong (CN)

(72) Inventors: **Jinglin Cai**, Guangdong (CN); **Yilin Wu**, Guangdong (CN); **Yuan Zhuang**, Guangdong (CN); **Sanliang Ruan**, Guangdong (CN)

(73) Assignee: **GUANGDONG OPPO MOBILE TELECOMMUNICATIONS CORP., LTD.**, Guangdong (CN)

(**) Term: **15 Years**

(21) Appl. No.: **29/888,533**

(22) Filed: **Mar. 31, 2023**

(30) **Foreign Application Priority Data**

Oct. 28, 2022 (CN) 202230718299.X

(57) **CLAIM**

The ornamental design for a mobile phone as shown and described.

DESCRIPTION

FIG. 1 is a perspective view of a mobile phone showing our new design;

FIG. 2 is another perspective view thereof;

FIG. 3 is further another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an enlarged view of area 10 circumscribed in FIG. 2.

The broken lines consisting of evenly spaced dash lines in the drawings depict portions of the mobile phone that form no part of the claimed design.

The broken lines consisting of short and long dash lines encircling the enlarged detail views are for annotative purposes that form no part of the claimed design.

1 Claim, 10 Drawing Sheets
